UNITED STATES PATENT OFFICE.

WALLACE V. WOLFE, OF GLEN RIDGE, NEW JERSEY, ASSIGNOR TO WESTERN ELECTRIC COMPANY, INCORPORATED, OF NEW YORK, N. Y., A CORPORATION OF NEW YORK.

POWER-LINE SIGNALING.

Application filed April 7, 1924. Serial No. 704,614.

This invention relates to communication by means of high frequency waves, and more particularly to communication over power lines by superimposing the high frequency waves upon the power currents traversing the power line.

An object of the invention is to provide for full duplex telephone communication over power lines.

10 Another object is to provide for full duplex telephone communication over power lines and to extend the communication by means of low frequency circuits to additional stations at points remote from the power line.

20 Another object is to provide for connecting signaling apparatus to a power line for transmission thereover by such coupling apparatus as will combine efficient signaling with safety to persons communicating by means of signaling apparatus and with safety to the apparatus itself.

25 Other objects are to provide for telephone and signaling operation over high power transmission lines in which the transmitting volume will be sufficient for transmission under both normal and abnormal conditions over either long or short lines, in which a full metallic high frequency circuit is employed in order to avoid the numerous difficulties connected with ground return circuits, and furthermore, to employ for communication such carrier frequencies as will not interfere with existing communication 30 systems and particularly with carrier wave telephone systems parallel with the power lines. An ancillary object is to avoid any interference of harmonics of the power line current, static or other impulsive disturbances, and other communication systems, with the power line signaling system.

40 A special object is to provide means for effectually centralizing the energy supply for the transmitting and receiving devices of a duplex telephone system.

An important object is to provide for safely and efficiently coupling high frequency signaling apparatus to high voltage transmission lines.

50 In a particular embodiment any desired number of high frequency translating stations, two or more, are coupled to two conductors of a three-phase transmission line operating at a voltage of the order of 110,000

volts. To each station is connected a local 55 telephone circuit in which is connected one or a greater number of telephone stations. The equipment at each high frequency station includes high frequency translating apparatus for generating, modulating, and am-

plifying high frequency waves to be transmitted to the power line, and for amplifying and detecting modulated high frequency waves received therefrom. It also includes 60 selective circuits by means of which the incoming and outgoing waves are confined to separate channels within the station, and a coupling circuit through which the high frequency apparatus is connected to the power line and which is especially adapted to prevent the voltages of the power currents entering the translating station. The local 65 telephone circuit is connected to the translating station through a bridge or "hybrid" coil by means of which the outgoing and incoming currents are separated and diverted to channels passing through the transmitting and the receiving apparatus respectively.

70 Separation of the low frequency incoming and outgoing currents by means of the bridge coil and of the high frequency currents by means of the selective circuits permits duplex communication over the system. Two carrier frequencies are used for the high frequency transmission, one of which 75

is always used for transmitting by any station originating a call and the other of which is always used by a called station in replying. The selective circuits at each station are adapted respectively to transmit 80

these frequencies; normally, that is in the idle condition of the station, the receiving apparatus is connected to the selective circuit that is adapted to transmit the frequency allocated to the calling station and 85

relays are provided by means of which the selective circuits are interchanged at a call originating station before communication begins. Station selection is accomplished by 90

means of a well known type of selector hereinafter described, which is combined with the high frequency circuit in such a manner to be properly actuated by incoming waves.

100 A high degree of protection of the high frequency apparatus and of the users of the telephone system against the high voltages of the power line is secured by the special features of the coupling circuit by means

- of which the apparatus is connected to the power line. Part of this circuit is comprised of impedance elements which are mounted within the same building as the high frequency apparatus and which have associated with them low voltage protective devices. Another part comprises high voltage condensers and high voltage protective devices mounted outside the station building.
- 10 The invention will be more fully understood both as to the details of its organization and its mode of operation by reference to the following description taken in connection with the accompanying drawings, of 15 which—
- Figs. 1 and 2 constitute a circuit diagram showing the essential features of the apparatus employed at one station and in its associated local circuit, and
- 20 Fig. 3 shows a possible layout of the several groups of apparatus constituting the coupling circuit.
- In the circuit shown in Figs. 1 and 2, 4 is a low frequency telephone circuit to which 25 may be connected four telephone stations two of which, 1 and 2, are shown in complete circuit detail, and the connections to the others are indicated by the branch circuits 66 and 67. Station 1 is that of the 30 operator or party located at the translating station; station 2 and the others may be located at points remote therefrom. In effect the four local stations are connected in parallel between the two sides of the circuit 4.
- 35 The equipment of station 1, which will hereinafter be designated the operator's station, differs principally from that of the other stations, hereinafter referred to as extension stations, in that a separate battery is provided at the extensions for ringing and for 40 operating the microphone, whereas at the operator's station use is made of a common battery which provides also energy for space discharge devices and for relays in 45 the common local circuit. To isolate the batteries at the extension stations, the branches leading thereto are connected through condensers 6, which have large enough capacities to pass the speech currents 50 freely. The low frequency circuit is connected to the high frequency translating apparatus by means of bridge transformer 5, one output circuit of which includes the high frequency transmitting apparatus and 55 the other the receiving and detecting apparatus, separate incoming and outgoing channels for the signaling currents being thus provided within the translating station. The outgoing channel includes the apparatus for generating and transmitting modulated carrier waves, comprising a signal or speech amplifier 8, a high frequency oscillator 7, a modulator 9, and an auxiliary amplifier 10 adapted to amplify the modulated 60 high frequency waves produced by the
- modulator 9. Ordinarily the amplifier 10 is not used, being provided for emergency use as hereinafter described, and the outgoing channel is normally continued from the output of the modulator through the contacts 70 of relay 40 to a high-pass filter 11 which is adapted to transmit the higher of the carrier frequencies and to suppress the lower. The incoming circuit includes a multi-stage high frequency amplifier 15, a detector or 75 demodulator 16, and in its normal condition includes also a low-pass filter 12 which is adapted to transmit the lower frequency carrier wave and to suppress the higher. For calling purposes, the incoming channel is 80 extended from the output of the detector by means of relays through a separate channel to call signal devices at the several local telephone stations. This call signal channel includes a multi-position selector 17 to which 85 are connected individual signal circuits 47, 48, 49 and 50 leading to the local circuit telephone stations. The selector 17 is the type of device described and claimed in the patent to J. C. Field, No. 1,343,256, granted 90 June 15, 1920.
- A common source 56 is provided for the space current required by the space discharge devices 7, 8 and 9 of the transmitting apparatus and the amplifiers and detector of the receiving apparatus; the filamentary cathodes of these discharge devices are also supplied with energizing current from a separate common source 68. The control electrodes of the receiving devices are polarized by being connected to points of suitable potential in the cathode circuit. In the transmitting apparatus, larger polarizing potentials are required than can be obtained 100 from the cathode circuit alone and these are provided in part by the potential drop in a resistance 57 which is inserted in the space current circuit between the negative terminals of the cathode current source 68 and space current source 56, and in part by the 105 fall of potential in the cathode circuit. By this means, full advantage is taken of the potential difference necessary for the heating of the filaments and the additional potentials required are secured at the cost of a 110 minimum expenditure of energy and with the advantage of the elimination of separate polarizing batteries.
- 115 It is commonly the case in the operation of systems of this type that a station may be idle for relatively long periods and it is desirable that the energy required to operate the apparatus be conserved during such periods. The receiving apparatus must continuously be ready to receive incoming calls 120 and for this reason the space discharge tubes must be continuously energized. The greater amount of energy, however, is taken by the discharge tubes of the transmitting apparatus, and this may be saved by deenergiz- 125
- 130

ing these tubes during the idle periods. As a result of the presence of resistance 57 in the common branch of the space current supply circuit, the establishment of the space current in the transmitting devices would cause a drop in the potential applied to the receiver anodes and an undesirable change of sensitivity in the receiver. To prevent this, the receiver discharge tubes are operated at a potential somewhat lower than that of the transmitter, the reduced potential being secured by means of resistances 58 and 59 which are inserted in the separate space current circuit to the receiver, and a relay circuit is provided which simultaneously with the establishment of the space current in the transmitter short circuits the resistance 58, thereby maintaining the receiver anode voltage and space current at steady values.

For efficient signaling it is essential that the signaling circuit be connected with the power line in such a manner as to effect a suitable transfer of energy from the signaling circuit to the line and from the line to the signaling circuit. For protection of the signaling apparatus and persons communicating thereover, it is essential that direct contact with the high voltage lines be avoided. The coupling condensers 14 may comprise any suitable arrangement whereby a capacity of a sufficiently large value is provided between the terminals of the signaling circuit and the conductors of the power line. Such a capacity may be provided by a fixed condenser adapted to withstand the high voltages or an arrangement of aerial wires arranged adjacent to the power line conductors. It has been proposed to employ a section of high voltage cable, the cord of which constitutes the power line conductor and the sheath of which serves as a plate of a condenser to which the signaling circuit is connected. However, the manufacture of cable adapted to continuously withstand the high voltages met with is a matter of considerable difficulty. The preferred coupling arrangement consists of fixed condensers having an oil dielectric or a composite dielectric comprising plates of glass immersed in oil, and being contained in substantial waterproof metal tanks provided with high voltage insulators of such type as is commonly used in high voltage out-door installations. The coupling circuit comprises condensers 19 and choke coils 20 in series with the line and condensers 21 and choke coils 22 in shunt to the line. The coils 22 serve also to shunt to ground any 60 cycle current entering the coupling circuit. Choke coils 23 are connected in the line adjacent the coupling condensers 14. Safety devices comprise fuses 24, open air spark gaps 25 and 26 of high current capacity and vacuum gap 27 in shunt to the gaps 26.

The vacuum gap breaks down quickly under the influence of excessive voltages, and thus serves to protect the signaling circuit until the air gaps 26, which are adapted to carry a much heavier current than the vacuum gap, come into operation. Fuses 62 and disconnecting switches 61 are provided between the choke coils 20 and 23 for additional protection and to permit the high frequency apparatus being disconnected from the power line. Further protection of the high frequency apparatus is furnished by the protective device 60 inserted between the channel filters and the coupling circuit. This device is the type commonly used for the protection of telephone stations and comprises fuses inserted in the line and low voltage bridging discharge gaps. Part of the coupling circuit is installed within the building used to house the high frequency apparatus, the enclosing wall of the building being indicated at 63 into which are built high voltage insulators 64 for the outgoing leads. A second part including choke coils 22 and 23 and condensers 21 is mounted within a closed compartment 65 which is mounted outside the station building. The remaining elements including the high voltage condensers 14 and discharge gaps 25 are mounted outdoors adjacent to the power line without additional protection against the weather. A possible physical organization of the coupling circuit is shown in Fig. 3 in which the numerals designate the same elements as they designate in Figs. 1 and 2. The arrangement is shown in elevation, duplicate elements not being shown. The compartment 65 containing the intermediate group of elements is mounted on a pole 71 on which is also mounted the open air discharge gaps 25, one pole of which is connected to ground through conductor 70. Within the building the station apparatus is mounted on vertical panels 69, the figure showing an end elevation of these.

Operation in calling from operator's station.

When the operator at station 1 takes his receiver from the switchhook, the contact 32 is closed, thereby connecting ground to the conductor 33. The relays 34, 35 and 36 then operate. The operation of relay 35 causes battery to be applied to conductor 72 and since the circuit of selector key SK is normally open, relay 37 is caused to operate and also relays 40 and 41. It will first be assumed that line conditions are normal and that the auxiliary amplifier 10 is not to be used, in which case the switch 51 is closed in the left hand position. The relay 36 closes the filament heating circuits of the space discharge devices 7, 8 and 9 and also of the auxiliary amplifier 10. The heating of the filaments in the devices 7, 8 and 9

causes the space current circuits therefor to be completed, current being supplied from the source 56 and the devices being then completely energized. The operator now 5 actuates one of the keys SK corresponding to the station he desires to call. The operation of the selector key alternately opens and closes a short circuit around the relay 37 in accordance with a predetermined code 10 and thereby causes the condenser 38 to be added to the oscillating circuit of the oscillator 7 intermittently in accordance with the code. Normally, the high-pass filter 11 is connected to the transmitting channel and 15 the low-pass filter 12 is connected to the receiving channel. However, the operation of the relays 40 and 41 following upon the operation of relay 34 causes the filters to be interchanged so that the low-pass filter 12 20 is connected to the transmitting circuit. During the operation of the selector key, the frequency generated by the oscillator 7 is thus changed back and forth from the low carrier frequency to the high carrier frequency, and vice versa. However, the high 25 carrier frequency is not transmitted to the line inasmuch as the low pass filter suppresses it, the result being that groups of waves of the low carrier frequency alone are 30 transmitted to and impressed upon the power line. When the selected station answers, the operator may converse, by means of his telephone set, with the party at the selected station. The operation of 35 the selector key is prevented from affecting the relays 40 and 41 by the resistance 73 which is included in the circuit of relay 37 but which is not short circuited by the key. In addition to operating relay 36 and completing 40 the circuits of relays 37, 40 and 41, the operation of relay 35 causes a short circuit to be placed around the resistance 58, thereby annulling the effect on the receiver space current due to the establishment of 45 space current in the transmitter. It further places a short circuit around the marginal relay 42, thereby preventing incoming carrier waves from affecting the established condition of the calling station. The station 50 originating a call always transmits on the lower of the two carrier frequencies and receives on the higher. If desired, the high frequency may be used for calling and the lower for answering.

55 *Operation in calling from an extension station.*

60 When the party at an extension station such as 2 removes his receiver from the switchhook, a local circuit is completed through contact 74 and the relay 45 operates, connecting ground to conductor 75 and causing the relays 30 and 35 at the translating 65 station to operate in sequence. The opera-

tion of relay 35 conditions the high frequency apparatus for transmission as already described in connection with the operation in calling from the operator's station. The operator now actuates one of the keys 70 SK' corresponding to the station he desires to call, thereby intermittently grounding the conductor 76 in accordance with the predetermined code. Relay 31 at the translating station is thus intermittently operated, 75 following the code of the selector key and creating an intermittent short circuit around the relay 37 also in accordance with the impulses created by the selector key. In other respects the operation of the system from a 80 remote station is the same as the operation from the operator's station.

85 *Operation at a called station.*

The electrode circuits of the amplifier 15 and the detector 16 are normally energized. Incoming high frequency waves are detected by the detector 16, causing an increase in the space current thereto and operating the marginal relay 42, provided that the called station is idle. If, however, the called station is not idle, the relay 42 could not operate on account of the short circuit placed around it by the operation of relay 35 as hereinbefore described. The operation of the relay 42 causes relay 43 to operate and the relay 44 in sequence, the circuit of relay 44 being completed through the left hand contact of relay 43. Incoming groups of waves determined by the selector key at the calling station cause the relays 42, 43 and 44 to operate and the selector 17 to step in accordance with the code of the received impulses. The stepping of the selector 17 causes the contact arm 77 to select one of the lines 47, 48, 49 or 50, thereby connecting it to ground momentarily through the spring contact 78. If the line 47 is selected corresponding to the operator's station, the momentary connection to ground causes lock-up relay 28 to operate and the signal bell 18 to ring. If the line selected is 48 corresponding to the extension station 2, a similar lock-up relay is operated. Battery is applied to a third conductor 79 105 extending to the remote station and terminating in a relay 29, the operation of which closes a local circuit, thereby operating a signal bell. After the code signals have been transmitted and while the calling operator 110 is awaiting the response of the called party, a continuous train of waves of the lower carrier frequency is being received by the detector 16 and the marginal relay 42 is maintained continuously operated. In the 115 absence of impulses, the selector 17 is restored to its normal position and the momentary ground is removed from the selected circuit. However, by virtue of the lock-up feature of the ringing relays 28, a 120

continuous call signal is maintained at the called station. When station 1 is called and the operator removes his receiver from the hook and places ground upon the conductor 5 33, the operation of relay 34 breaks the circuit of the lock-up relay 28, thereby stopping the ringing signal. The operation of relay 35 follows in sequence after the operation of relay 34, but on account of the relay 43 10 being operated the functions that the relay 35 can perform are limited to short circuiting the resistance 58 and causing the operation of relay 36 to energize the transmitting apparatus. Relay 37 remains unoperated, 15 whereby the oscillator 7 is caused to generate waves of the higher carrier frequency. Relays 40 and 41 also remain unoperated whereby the high-pass filter remains connected to the transmitting apparatus and 20 the low-pass filter to the receiving apparatus. The called station thus always transmits on the higher of the two carrier frequencies and receives on the lower. Of course, the use of the frequencies may be the 25 reverse of that stated, if desired. If the called station is an extension station, such as 2, the removal of the receiver from the switchhook in response to the call by closing the contact 74, energizes the relay 45 at the 30 extension station and in sequence the relay 30 at the translating station. Relay 30, functioning in the same manner as relay 34, breaks the circuit of the lock-up relay, thereby 35 stopping the bell at the extension station and at the same time operates relay 35. In this case, the further operations are the same as described in connection with the response of station 1 to an incoming call.

40 Operation at an idle station.

When oscillations of the frequency used by a call originating station are impressed upon the line, the relays 42, 43 and 44 are actuated once for each group of waves. 45 However, as the arrangement of the groups is not one of those for which the selector 17 is set, the selector does not close any of the call signal circuits and at the cessation of the incoming impulses returns to its normal 50 position. In order that the party at one of the idle stations wishing to make a call may avoid breaking in on a conversation that is already in progress, it is desirable that means be provided to indicate when the line 55 is busy. In the system described, this indication is provided in the form of an audible busy signal. The receivers of the several telephone sets associated with a translating station are permanently connected in circuit, 60 so that any conversation that is taking place over the system is made audible at all stations without the receiver having to be removed from the switchhook. Operators at 65 idle stations are thus warned not to attempt to call upon the circuit whereby they are

able to avoid interfering with conversations in progress.

Emergency key operation.

If line conditions are too abnormal to 70 allow code selective ringing, if the selector circuits are not operating properly, if there are only two stations upon the line, or, if it is desired to arrange so that all the stations may be called simultaneously from a 75 chief operator's station, the key 46 may be operated. High frequency impulses put upon the line will then cause the relay 43 to close a circuit directly through all of the locking relays 28 and the lines 47, 48, 80 49 and 50, which have been connected together, thereby causing a simultaneous ringing signal at all of the local stations.

Auxiliary amplifier circuit operation. 85

If line conditions are bad owing to a break in the line or a section of the line being down, the switch 51 is moved from its normal left hand position to the right hand position. The outgoing channel will then 90 extend from the plate circuit of the amplifier 9 through the high frequency transformer 54 to the grid circuit of the amplifier 10 and from the plate circuit of the amplifier 10 through the high frequency transformer 95 55 and the high or low pass filter 11 or 12, as the case may be, to the line. Closing the switch 51 in its right hand position connects a power source 52 to a motor generator 53 which furnishes space current 100 to the power amplifier 10. The filament current of the amplifier 10 is furnished from the common source 68 and is controlled as hereinbefore described by the relay 36. The 105 amplifier 10 is of a type capable of supplying from five to twenty times more energy than is normally used for transmitting.

It is contemplated that the coupling circuit 13 should have the transmission characteristic of a very flatly tuned circuit or preferably that it should have the characteristic of a band pass filter, thus transmitting with negligible attenuation currents of frequencies from 80,000 to 100,000 cycles per second or whatever frequencies are used in the particular system. A band pass filter passes a band of frequencies with substantially uniform and small attenuation and greatly discriminates against currents of other frequencies. Such a band filter characteristic 110 may be obtained by properly choosing the capacities 19 and 21, inductances 20, 22 and 23, and the capacities 14. An advantage of a band pass filter in this connection is that 115 it discriminates not only against the low frequencies of the power line, but also against high frequency waves such as may be picked up by the interception of radio signals or by the action of atmospheric static 120 discharges.

A feature of the local circuit is the use of the artificial line 55 in series with the operator's telephone station. The purpose of this line is to limit the amount of energy received at the local station to about the same value as that received at the remote stations, whereby uniform transmission is secured at all points.

An additional feature of the operation of the system is that the party at any one of the stations of the local circuit connected to a translating station may call any of the other stations in the same local circuit. Calling is accomplished in the same manner as calling a distant station, a selector key corresponding to the code signal of the local station called being operated. The operation of the selector key places a ground on the circuit including the selector operating relay 44, either directly if the calling station is the operator's station 1 at the translating station or indirectly through the contact of relay 31 if the call originates at station 2 or another of the extensions.

25 What is claimed is:

1. A signaling system comprising a high frequency transmission channel, a wave translating system connected to deliver high frequency wave energy thereto, a control circuit operatively associated with the translating system to condition it for the production of high frequency waves, a second control circuit adapted to control the frequency of the high frequency waves, a two wire line extending from the translating system to a remote low frequency wave signaling system, the conductors of said two wire line being conductively isolated from each other, and relay circuits operatively connected with each of said control circuits to extend the control of the translating station to the remote signalling station, each relay circuit including respectively one conductor of the said two wire line.

45 2. A power line signaling system comprising a power transmission line, a high frequency wave translating system connected thereto and including a space discharge oscillator, a source of power for said oscillator, a telephone line connected to said translating station and extending to a remote telephone station, a relay circuit adapted to connect said oscillator to said power source, and a second relay circuit adapted to control the frequency determining elements of the oscillator, the conductors of said telephone line being conductively separated from each other and included respectively in said relay circuits whereby the control of the translating station is extended to the remote telephone station.

60 3. A power line signaling system comprising a power transmission line, a high frequency wave translating system connected thereto, a control circuit operatively asso-

ciated with the translating system to condition it for the production of high frequency oscillations, a second control circuit adapted to control the frequency of the high frequency oscillations, a plurality of telephone lines connected together in parallel and extending from said translating system to a like plurality of remote telephone stations, the conductors of said lines being conductively insulated from each other, and relay circuits corresponding to each of said lines, operatively associated with each of said control circuits and extended in pairs to the remote control stations through the separate insulated conductors of the lines.

70 4. In a signaling system in accordance with claim 2, a telephone receiver at said telephone station, said receiver being continuously connected to the telephone line recited in claim 2 whereby a busy condition 75 of the circuit is audibly indicated.

5. In a two-way signaling system, transmitting apparatus and receiving apparatus including space discharge devices, a common source of space current for said devices, 80 means for changing in intensity the space current to said transmitting apparatus and additional means rendered effective upon the actuation of said intensity changing means to annul the effect of the changes upon the space current of said receiving apparatus.

85 6. In a signaling system, transmitting apparatus and receiving apparatus including space discharge devices, space current circuits connected to said devices and to a common current source, said space current circuits including a common branch containing an impedance, means for independently interrupting the space current to said transmitting apparatus, and additional means rendered effective upon the operation of said interrupting means for annulling the effect of said interruption upon the space current 95 of said receiving apparatus by changing in 100 a compensating manner the impedance of the supply circuits therefor.

105 7. In a signaling system, transmitting apparatus and receiving apparatus including space discharge devices, space current circuits for said transmitting apparatus and receiving apparatus including a common current source and having a common path containing as impedance, the space current circuit for said transmitting apparatus being normally interrupted and the space current circuit for the receiving apparatus being continuously closed, a second impedance included in an independent branch of the space current circuit of the receiver, means 115 for independently establishing the space current to said transmitting apparatus and additional means, effective upon the operation of said first mentioned means to short circuit 120 said second impedance.

8. In a signaling system a signal modifying apparatus comprising a plurality of space discharge devices having control electrodes and filamentary cathodes, a source of heating current for said cathodes, and a source of space current for said discharge devices, at least one of said control electrodes being negatively polarized with respect to its cathode in part by the potential of said 10 heating source and in part by the potential of said space current source.

9. In a signaling system, a signal modifying apparatus comprising a plurality of space discharge devices having control electrodes and filamentary cathodes, said cathodes and source of heating current therefore being connected in a series circuit, a space current circuit connected between the anodes of said devices and a point in the cathode heating circuit, a source of current included in said circuit, a resistance included between the cathode circuit and the negative terminal of said source, and conductive circuits connecting said control electrodes to said resistance whereby at least one of said control electrodes is polarized with respect to its associated cathode in part by a potential drop in the cathode heating current and in part by a potential drop in the space current circuit. 25

10. In a system for signaling over high voltage power lines, a station building containing high frequency translating apparatus, a high voltage power line outside said building, and a broad band filter for coupling said high frequency apparatus to said 30 power line, said filter comprising a plurality of groups of impedance elements, one of said groups including terminal condensers adapted to be connected to said line and to withstand the voltages thereof and being located adjacent thereto outside said building, another of said groups being located within said building, and each of said groups including voltage operated protective devices. 35

In witness whereof, I hereunto subscribe 40 my name this 5th day of April A. D., 1924.

WALLACE V. WOLFE.
